FEELER APPARATUS FOR CONTROLLING
WRENCH ROTATION

Sidney P. Johnson, Washington, D. C.

Application July 11, 1952, Serial No. 298,484

5 Claims. (Cl. 81—53)

(Granted under Title 35, U. S. Code (1952),
sec. 266)

1

This invention relates to tools and more particularly to a wrench for accurately rotating a nut or the like a small predetermined amount.

The described invention may be manufactured and used by and for the Government of the United States of America for governmental purposes without payment of any royalties thereon or therefor.

It has been found that, when pipe flanges are bolted together, an undesirable torsional stress sometimes remains in the tightened bolts and this stress should be relieved if the coupling is to have maximum holding strength. In fact, certain pipe-fitting and coupling instructions often require this relief by specifying that the nuts on the bolt-studs be backed off one-half a degree. However, in practice, such requirements for the most part were ignored or intentionally overlooked because of the inability of the mechanic to estimate the necessary degree of loosening and the dangers inherent in any excessive loosening. Some special tools which deal generally with such problems have been proposed, but these operate on an entirely different principle in that they are concerned solely with assuring an initial tightness of the nut rather than with relieving strain by loosening the nut a predetermined amount.

Accordingly, one of the broader objects of this invention is to provide a wrench by means of which a nut or the like may be rotated in either direction any accurately gauged amount; while a more specific and related object is to provide a wrench capable of backing-off nuts a small fractional part of a turn sufficient to relieve undesirable torsional stresses in the bolt on which it is mounted.

Further objects are to provide a wrench that can easily be adjusted to fit over the nut to be moved; that can be used for different-sized nuts; and which is simple to operate and economical to construct.

Other objects of this invention will be readily appreciated by reference to the detailed description.

In accordance with the invention, the wrench embodies a nut-engaging portion and extensible thrust and stop members adapted to be brought into engagement with any available fixed surface lying in proximity to the nut. In operation, the wrench is engaged with the nut, and the stop member adjustably set at a predetermined distance from the fixed surface, which, in effect, is both a referencing and supporting surface. The thrust member then is brought up to and forced

2

against or into the fixed surface, this force or thrust reacting on the wrench in the manner to be expected to cause it to rotate to the limit of its stop member. The stop member does not have to be a type having a fixed feeler settable with its inner end a predetermined distance from the reference surface and then swung into physical contact with that surface. Instead, it may be found desirable to reverse this operation and obtain an indication, by means of a spacer plate or dial, of the distance by which a stop member having an initially engaged feeler moves away from that surface. In fact, for some purposes it may be found preferable to utilize a stop member having a plunger-type feeler adapted to maintain constant contact with the reference surface during the whole time that the stop member as a unit is swung toward or away from this surface, and the wrench-limiting factor in such an instance may be provided by variations in the pressure exerted on the feeler by that surface. Preferably, the gripping jaws of the wrench are formed on suitable removable and replaceable adapters or bushings sized to engage nuts of various diameters, and the adapters are so formed as to permit the nuts to be engageable regardless of their angle of rotation with respect to the wrench.

The preferred form of the invention is illustrated in the accompanying drawings, of which Fig. 1 is a plan view showing the tool operatively engaging a pipe flange nut; Fig. 2 a side elevation of the Fig. 1 assembly; Fig. 3 a sectional view taken along line 3—3 of Fig. 2, Fig. 4 a perspective view of the nut-receiving bushing, Fig. 5 a gauge that may be used for indicating the amount of nut movement; and Fig. 6 is a plan view of a modified wrench.

Referring to the drawings, the wrench, generally designated by numeral 10, is formed of an elongate arm or body 12 provided centrally with head portion 14 adapted to grip and loosen nuts, such as nut 22, used to couple a pipe flange 16 to an adjacent flange, or the like. The nuts are engaged or gripped by a bushing 18, that is provided with a nut-receiving socket 20, the bushing 18 being removably received in a recess 24 formed in the body portion of the wrench.

The action of the wrench relies in part upon the previously referred to fixed reference surface in that, before the wrench is operated, it must be set in a certain position with respect to this surface, rotation of the wrench from that position determining and conforming to the desired degree of nut rotation. In the assembly shown in

Fig. 1, the fixed surface is pipe flange 16, although, in other adaptations the fixed surface can be any surface that lies proximate to the nut, or, if desired, the wrench itself could be provided with a fixed surface.

The configuration or shape of the wrench will depend somewhat upon the principal purpose for which it is intended, the wrench illustrated being somewhat arcuate in shape and having oppositely extending arm portions 32 and 34 projecting laterally from the central portion of its body. As may be seen, these arms are set at a slight angle so as to permit them to be brought into a spaced relationship with respect to the pipe flange against which the wrench is used. Arm 32 mounts a thrust member 36 which, as shown, simply is a threaded bolt having an operator's handle 37, secured at its outer end, the inner end of this bolt being adapted to flushly engage pipe flange 16. Opposite arm 34, similarly, is provided with a threaded opening to receive a set screw 38 that is adapted to be adjustably fed through the arm by a knurled head 40.

The manner in which this wrench is used should be somewhat apparent from the foregoing description. Its primary purpose is, as has been stated, to relieve undesirable torsional stresses set up in bolts by the tightening of the nuts on them. These stresses must be relieved and the present wrench is adapted to relieve them by gripping the nuts and "backing them off" the exact degree required. To engage the nuts a suitable adapter or bushing 18, which is sized to fit the nut being loosened, is selected, this adapter being fitted over the nut and then by teeth 25 engaged with corresponding teeth 26 of the recessed body portion of the wrench. As may be appreciated, the nut rarely will lie in the particular rotated position shown in Fig. 1, but, such an eventuality easily is accommodated since the wrench can be fitted in a variety of positions over the adapter after it has been mounted on the nut. For this purpose it is desirable to use rather closely-spaced teeth so as to increase the number of positions in which the adapter and the wrench can be intermeshed.

With the nut engaged, arms 32 and 34 will lie in their spaced relationship to pipe flange 16 and thrust member 36 may be fed inwardly toward the flange to bring its inner end in contact with it. The degree that the wrench is to be turned, however, is a function of set screw, or stop 38 and this stop is adjusted until its inner end lies a certain spaced distance from its radially adjacent flange surface. Such a spacing is designated by small arc X (Fig. 1) which is determined both by the dimensions of the wrench and the desired degree of backing-off of the nut. For example, with a wrench having a designed dimension of three inches from the center of nut 22 to the contact point of set screw 38, the spacing required to back-off a nut one-half degree of rotation is 0.0262 inch and, for other wrenches and other desired rotations suitable charts readily can be prepared.

With set screw or stop 38 fixed in its predetermined position, nut 22 may be loosened the precise amount desired simply by rotating the handle of thrust member 36, this rotation forcing the thrust member inwardly against flange 16 of the pipe and causing the wrench to rotate about the axis of nut 22 until the rotation is stopped by engagement of the inner end of stop 38 with the pipe flange.

In actual practice it has been found desirable,

in order to obtain a precise setting of stop 38, to first force thrust member 36 into such a firm contact with pipe flange 16 that any looseness between bushing 18 and the nut is taken up. With this looseness taken up, set screw 38 can be adjusted accurately by inserting a suitable spacer plate (not shown) between stop member 38 and the outer surface of the flange, this plate being removed after it has been contacted by the stop. Of course, the spacer must have a thickness equal to the desired X spacing.

Fig. 5 illustrates a modified form of a stop member 38 in which the necessity of using such a spacer plate is avoided by the use of a suitable dial gauge 42 that can be calibrated in inches or in degrees to give a direct reading of the spacing of its inner end. Such mechanism is obtainable commercially and should need no detailed description.

If felt desirable, an operable tool would be provided even if both the thrust and the stop members were disposed on the same side of the body portion although, in such an event, the degree of rotation would be the amount by which the stop member moved away from its fixed reference surface. Such a modification is illustrated in Fig. 6 which shows a wrench 44 having a head portion 46 formed at one end of a body 48, a thrust member 50 and a stop member 52 being mounted on the same side of the body. Stop member 52 may include a set screw, such as screw 38 of Fig. 1, in which event the degree of rotation (in counter-clockwise direction) would measure the amount the set screw is moved away from the fixed reference surface; or, if desired, the stop member may include a conventional engagement with the fixed reference surface during wrench movement whereby to indicate the movement of the stop member ratchet mechanism 58 may be provided on the handle 60 when turning space is not available.

The advantages of the present wrench are rather obvious in that, primarily, a simple, inexpensive and easily-used tool is provided for producing any minute degree of rotation desired. The above description has been with reference to the use of the tool for backing-off tightened nuts, but it will be appreciated that the tool could easily be adapted for turning most any rotatable object. Further, it will be appreciated that the function of the thrust and the stop members could be accomplished by many other means which are intended to be within the compass of the invention.

Obviously many modifications and variations of the present invention are possible in the light of the above teachings. It is, therefore, to be understood that within the scope of the appended claims the invention may be practiced otherwise than as specifically described.

I claim:

1. A wrench for turning a rotatable head mounted in proximity to a fixed support, said wrench comprising an arm formed to grip said head, a stop having a feeler member, and a thrust member, said members being adjustably projected outwardly from said arm toward said fixed support and said thrust member being adapted to be forced against said fixed surface when said head is gripped, whereby said stop can be set a predetermined distance from said support and said thrust member forced against the surface, said force causing the wrench to swing about the axis of said head to the limit of said stop.

2. A wrench for turning a rotatable head mounted in proximity to a fixed support, said wrench comprising an arm having an intermediate portion adapted to grip the head, a stop having a feeler member and a manually operable thrust member, each member being adjustably carried at opposite end of said arm and projecting outwardly therefrom toward said fixed support, whereby said wrench can be engaged with said head with said feeler member set a predetermined distance from said fixed support, said thrust member then being movable into contact with and thrust against said fixed support to swing reactively said arm about the axis of said engaged head until the feeler member engages 15 the support.

3. A wrench for turning a rotatable head mounted in proximity to a fixed support, said wrench comprising an arm having an intermediate portion adapted to grip the head, a stop 20 having a feeler member, and a manually operable threaded member, each member being adjustably carried at opposite ends of said arm and projecting outwardly therefrom toward said fixed support, whereby said wrench can be engaged with 25 said head and said feeler member set at a predetermined distance from said fixed support, said threaded member then being movable into contact with and thrust against said fixed support to swing reactively said arm about the axis of 30 said engaged head until the feeler member engages the support.

4. A wrench for turning a rotatable head mounted in proximity to a fixed support, said wrench comprising a body having an intermediate portion adapted to grip the head, a stop having a feeler member and a manually operable thrust member each member being adjustably carried at opposite ends of the body and projecting toward said fixed support, said stop having 35 40

an indicator dial, whereby said thrust member can be moved into contact with the support and said feeler member set by means of the dial a predetermined distance from the support, said thrust member being movable toward said support to rotate the body about the axis of said engaged head until the feeler member engages the support.

5. A wrench for turning a rotatable head mounted in proximity to a fixed support, said wrench comprising a body having a detachable bushing formed to grip said head, a stop having a feeler member and a manually operable thrust member, each member being adjustably carried at opposite ends of the body and projecting toward said fixed support, whereby said thrust member can be moved into contact with the support and said feeler member set a predetermined distance from the support, said thrust member movable toward said support to rotate the body about the axis of said engaged head until the feeler member engages the support.
